FROZEN FOOD TRAY

Glenn David Boyd, Haddonfield, N.J., assignor to Campbell Soup Company, Camden, N.J., a corporation of New Jersey

Filed Nov. 12, 1963, Ser. No. 77,343

Term of patent 14 years

(Cl. D44—10)

FIG. 1.

FIG. 2.

FIG. 3.

FIG. 4.

FIG. 5.

FIG. 6.

FIG. 7.

FIG. 9.

FIG. 8.

FIG. 1 is a perspective view of a frozen food tray showing my new design;

FIG. 2 is a top plan view thereof;

FIG. 3 is a rear elevational view thereof;

FIG. 4 is a right side elevation view thereof;

FIG. 5 is a bottom view thereof,

FIG. 6 is a longitudinal sectional view of the frozen food tray of FIG. 1, taken on line 6-6, FIG. 2;

FIG. 7 is an enlarged fragmentary sectional view taken on line 7-7, FIG. 2;

FIG. 8 is an enlarged fragmentary sectional view taken on line 8-8, FIG. 2; and

FIG. 9 is an enlarged fragmentary sectional view taken on line 9-9, FIG. 2.

I claim:

The ornamental design for a frozen food tray, as shown.
